UNITED STATES PATENT OFFICE.

JOSEPH KABAT, OF GLOVERSVILLE, NEW YORK.

BASEBALL GLOVE.

Application filed August 1, 1924. Serial No. 729,530.

This invention relates to an improved base ball glove and while it has more particular reference to the type of glove to be used by infielders and outfielders, it is not 5 to be restricted to this particular use since the invention is adaptable for incorporation in mitts of the kind used both by catchers and first basemen.

The invention relies more particularly 10 for its novelty on the specific construction of the thumb of the glove. Heretofore, so far as I know, all base ball gloves have a seam which encircles the base of the thumb at its point of juncture with the main or 15 body portion. This seam is particularly objectionable, especially on the face of the glove owing to the shearing action to which the threads are subjected by the constant pounding of the ball in the glove. Also, 20 this front portion of the seam is subject to abrasion and the life of the marketed types of gloves is thus impaired to a very noticeable extent.

What I aim to do is to provide a glove 25 which does not have a seam extending from the base of the index finger to the base of the thumb and across the front of the glove. I have therefore conceived of and evolved a glove provided with a thumb wherein the 30 objectionable seam is entirely eliminated, both on the front and rear sides of the thumb. Thus, I have produced a very novel glove which is very strong and durable, one which conforms more accurately to the 35 shape of the player's hand, and one wherein the player's ability will be aided by the tendency of the ball to "stick" in the glove.

More specifically, I have devised a new 40 form of base ball glove wherein a single piece of material serves to form the facing for the fingers and thumb and also the backing for the little finger, the backing pieces for the remaining fingers and thumb being of separate pieces of material.

45 Other features and advantages of the invention will become apparent from the following description and drawing.

In the accompanying drawing forming a 50 part of this application and in which like numerals are employed to designate like parts throughout the same:

Figure 1 is a front elevation of a base 55 ball glove constructed in accordance with the present invention.

Figure 2 is a rear elevation thereof.

Figure 3 is an elevation or top plan view

of the blank of material utilized to form the facing for the glove.

Figure 4 is a detail view of the backing 60 piece for the improved thumb.

As before intimated, the glove is primarily composed of a facing formed from a single blank 1 of suitable material such as leather, chamois skin or the like. This blank is so shaped as to practically form the complete covering for the little finger. The backing pieces for the index and intermediate fingers designated by the reference character 2 are substantially of conventional design. The backing piece 3 for the 70 improved thumb structure is new. As is usual, when the several pieces of material are properly stitched together, the glove is padded and the padding is retained in place 75 by suitable lacing 4, the thumb and index finger being connected together in the usual way by a strap 5.

Referring again to the blank 1, it will be seen that the same is cut as to provide facing for the index finger 6, middle finger 7, 80 third finger 8, little finger 9 and thumb 10. Particular emphasis is to be given the inclusion in this blank of the portion utilized to form the facing for the thumb. The blank also includes a wing 11 for forming 85 the rear side of the little finger and an extension 12 to which the usual strap 13 is connected. It is also to be pointed out that the blank is provided with a pointed or V-shaped tongue 14 between the index finger and the thumb.

It is obvious that when the glove is completed by stitching the several parts together, the seam 15 at the bottom and rear side of the index finger (see Fig. 2) and the 95 adjacent end of the seam 16 of the thumb are disposed in diverging relation with the apex disposed at the margin of the opening 17 in the back of the glove. The seam 16 then extends up and over the end of the 100 thumb and then down along the side as indicated at 17 (see Fig. 1) after which it takes a turn and extends across the rear side of the glove as seen at 18 and ends at the binding surrounding the opening 17. Thus, 105 the usual seam that surrounds the bottom or base of the thumb is eliminated.

I wish it to be understood that the blank 1 as seen in Figure 3 may also serve to represent a pattern from which the facing pieces for the glove may be formed. The 110 small notches as seen at the various points

serve to permit the parts to be properly aligned and to insure perfect shaping of the material.

Believing that the advantages of the improved construction have been made apparent, I do not deem it necessary to enter a more lengthy description.

Having thus described the invention, what I claim is:—

10 In a base ball glove, a trunk of a single piece of material for forming the front of the palm, fingers and thumb including a

body having finger, thumb and tab portions, there being one thumb portion, one tab portion, and a plurality of finger portions projecting from the body, the thumb portion extending at an acute angle to the index finger portion, the tab portion being V-shaped and extending to bisect the angle between the thumb and index finger portions.¹⁵

In testimony whereof I affix my signature.

JOSEPH KABAT.
